(57) **CLAIM**

The ornamental design for a low power pet monitoring camera, as shown and described.

DESCRIPTION

FIG. 1 is a front and right side perspective view of a low power pet monitoring camera showing my new design; FIG. 2 is a front elevation view thereof; FIG. 3 is a rear elevation view thereof; FIG. 4 is a right side elevation view thereof; FIG. 5 is a left side elevation view thereof; FIG. 6 is an enlarged top plan view thereof; FIG. 7 is an enlarged bottom plan view thereof; and, FIG. 8 is a rear and right side perspective view thereof. The broken lines are for purposes of illustrating portions of the low power pet monitoring camera that forms no part of the claimed design.
